Primary Examiner—Melody N. Brown(74) *Attorney, Agent, or Firm*—Dority & Manning, P.A.**CLAIM**

The ornamental design for a mirror mounting assembly, as shown and described.

DESCRIPTION

FIG. 1 is a front perspective view of a mirror mounting assembly according to the present design;
 FIG. 2 is a rear perspective view thereof;
 FIG. 3 is a front elevational view thereof;
 FIG. 4 is a rear elevational view thereof;
 FIG. 5 is a top view thereof;
 FIG. 6 is a bottom view thereof;
 FIG. 7 is a right side view thereof; and,
 FIG. 8 is a left side view thereof.
